United States Patent Office.

BENJAMIN F. WHITCOMB, OF CLAREMONT, NEW HAMPSHIRE.

Letters Patent No. 91,888, dated June 29, 1869.

IMPROVEMENT IN REED FOR LOOMS.

The Schedule referred to in these Letters Patent and making part of the same.

To all whom it may concern:

Be it known that I, BENJAMIN F. WHITCOMB, of Claremont, in the county of Sullivan, and State of New Hampshire, have invented a new and improved Reed for Weaving; and I do hereby declare that the following is a full and exact description thereof, reference being had to the accompanying drawings, and the letters of reference marked thereon.

The nature of my invention consists in the form of the dent or dart for the reed, the dart being constructed of iron or other metal, with two curved or oval faces, meeting so as to form two smooth and even, but not cutting-edges to the dart.

The darts made in this way present a surface which gives the least possible friction to the passage of the thread through the reed, and in a great degree removes the liability of the thread's breaking while the loom is in operation.

The dart is also made with a boss near each end, and upon one or both sides, so that, when placed in the reed, the bosses for any particular reed being always of a given thickness, and fitting side by side, the darts will always be at a uniform distance from each other, and will also be held firmly in place, and have no tendency to turn or twist in the reed.

The dart is also tied to the ribs of the reed, by passing the cord around the shoulder of the boss, so that the dart can never slip from its place in the reed.

In the accompanying drawings—

The reed is represented by the letters *a b c d*, *a b* and *c d* being the ribs, and *e e* the darts tied to the ribs.

A single dart is represented by *f g*, its form and the curvature of the faces being shown by the end section, at *g*.

The bosses are shown at *h*, and the shoulders at *s*. *o k* represent the style of dart heretofore used, and now in use in metallic reeds, its form being seen by the end-section at *k*.

m represents cross-sections of two darts of the old style, in position, and *n* represents cross-sections of the improved darts when in position.

The advantages of this improvement, are—

First, diminution of friction on the threads, and securing them against breaking.

Second, the preservation of a uniform distance between the darts, by means of the bosses on them, and also securing them against turning or twisting in the reed.

Third, security of the dart in position, the shoulders of the boss, around which they are tied to the ribs of the reed, preventing them from sliding longitudinally.

What I claim as my invention, is—

A weaver's reed, with metallic darts, having oval faces meeting at the opposite edges, and with bosses on one or both sides of the dart, with shoulders as indicated, all constructed and arranged as and for the purposes specified.

B. F. WHITCOMB.
